UNITED STATES PATENT OFFICE.

JOHN W. SMALLWOOD AND DAVID R. AUSTIN, OF NEVADA, MISSOURI.

ROTARY ENGINE.

SPECIFICATION forming part of Letters Patent No. 402,625, dated May 7, 1889.

Application filed August 20, 1888. Serial No. 283,216. (No model.)

To all whom it may concern:

Be it known that we, JOHN W. SMALLWOOD and DAVID R. AUSTIN, citizens of the United States, residing at Nevada, in the county of 5 Vernon and State of Missouri, have invented certain new and useful Improvements in Rotary Engines; and we do hereby declare the following to be a full, clear, and exact description of the invention, such as will enable others skilled in the art to which it appertains to 10 make and use the same.

Our invention relates to improvements in rotary engines, the object of which is to provide a simple and durable device for a rotary 15 engine that will save steam, and one that will be easily reversed, and one that has no dead-centers, and the peculiar construction of the various parts of the device for the uses and purposes hereinafter specified. These objects we attain by means of the mechanism 20 illustrated in the accompanying drawings, in which—

Figure 1 is a view of the device, having the plate of one of the cylinders removed to show 25 the interior. Fig. 2 is a vertical cross-section of one of the cylinders on the line X X of Fig. 1. Fig. 3 is a longitudinal vertical section of both cylinders on the line Y Y of Fig. 1. Fig. 4 is a detail of the device for changing the 30 steam to reverse the engine. Fig. 5 is a detail showing the revolving valve. Fig. 6 is a view of one of the plates of the cylinder.

Similar letters of reference indicate corresponding parts in the several figures.

35 The rotary engine consists of two cylinders, one on each side of a steam-chest which is provided with a revolving valve, which alternately cuts off the steam first on one side and then on the other, and the revolving pistons 40 are placed so that their slots which contain the adjustable wings will be opposite to each other, so that when one piston is half-way round the other piston will be just starting.

45 A A are cylinder-casings of any desired size. Said cylinders have end plates, A² A² and A⁷ A⁷. The said end plates have grooves A⁶, which are circular in form, except on the side next to the supply and exhaust ports A⁵ A⁴, which are located close to each other on 50 opposite sides of the point A⁹, where the cyl-

inder-case S forms a close joint with the surface of the pistons B, so that the grooves in the end plates form a cam for the guiding of the wing D, which is permitted, by means of the slot B² in the piston, to drop down or back 55 as the paddle passes the abutment A⁹. Said end plates A² A⁷ are firmly bolted to each other by bolts A⁸; as shown, so that either cylinder may be easily and quickly opened to replace parts that are worn; and for this purpose and for the purpose of forming a tight joint the end or edge of the paddle D is provided with a groove, D², in which is placed a strip of any suitable durable substance for forming the packing of the cylinder, and beneath which is placed a spring of any desired kind for keeping the strip out against the cylinder as it and the strip wear by use. The spring F is preferably a long steel spring, as shown. The end plates A⁷ A⁷ also form the 60 ends of the steam-chest K. Said chest has a supply-pipe, K², which conducts the steam into the steam-chest.

I and I² is a revolving valve formed so that one end, I², will close the port A⁵ while the 75 other part is half-way round, as shown, the port A⁴ in the other cylinder being placed opposite the port A⁵, as shown. Thus but one of the ports is closed at a time, and then only for a short time, and that being while the 80 wing in the piston passes the space between the ports A⁴ A⁵ of the cylinder. The pistons and revolving valve are secured firmly to the driving-shaft C, which is provided with suitable bearings at E.

85 L is a reversing-box. It is provided with a reversing-valve, H, which has a handle, H², for turning it as desired. Said box has four openings, below which enter the cylinder and have passages which come together, one to 90 enter the steam-chest A⁵, the other to connect with the exhaust - passage A⁴. Reversing-valve H is so placed that it will cover two of the openings at once—one exhaust and one supply at the same time—or may be turned 95 so as to rest between the openings and thus throw the engine on a balance, and by turning still farther it closes the openings so as to reverse the engine.

H² is a winch secured to the reversing-valve 100

for turning the same, and to this crank is secured a lever, H³, by which both of the reversing-valves are operated.

Having thus described our invention, what we claim as new, and desire to secure by Letters Patent, is—

In a rotary engine, a reversing-valve, H, having a winch, H², ports A⁴ A⁵, a steam-box, L, cylinder-casings having grooves A⁶ and abutments A⁹, pistons B, having wing D, having spring-packing steam-chest K, revolving

valve composed of portions I and I², arranged as shown, and shaft C, all substantially as and for the purpose set forth.

In testimony whereof we affix our signatures in presence of two witnesses.

JOHN W. SMALLWOOD.
DAVID R. AUSTIN.
